SAFETY DEPOSIT BOX

Max Sorensen, 2404 Wicker St., Dallas, Tex. 75234

Filed Feb. 19, 1971, Ser. No. 117,219

Term of patent 14 years

Int. Cl. D31

U.S. Cl. D69—1

FIG. 1 is a perspective view taken from the front, top and left side of a safety deposit box embodying my new design;

FIG. 2 is another perspective view taken from the rear top and left side thereof, the right side being the same as the left side shown;

FIG. 3 is a top plan view thereof; and

FIG. 4 is a bottom plan view thereof.

I claim:

The ornamental design for a safety deposit box, substantially as shown and described.
